UNITED STATES PATENT OFFICE.

RALPH M. REEL, OF CUYAHOGA FALLS, OHIO, ASSIGNOR TO MARATHON RUBBER COMPANY, INC., OF AKRON, OHIO, A CORPORATION OF OHIO.

WASHBOARD.

Application filed November 1, 1922. Serial No. 598,404.

To all whom it may concern:

Be it known that I, RALPH M. REEL, a citizen of the United States, and a resident of Cuyahoga Falls, county of Summit, State of 5 Ohio, have invented certain new and useful Improvements in Washboards, of which the following is a specification.

This invention relates to new and useful 10 improvements in wash boards for laundry purposes, particularly that type of board which is provided with a rubber or rubber-like composition facing which is roughened to present a rubbing surface.

Wash boards of this type have been known 15 prior to my invention, but the purpose of the invention is to provide improved means for attaching the facing to the framework of the board to insure a firm hold for the facing. In previous constructions of this 20 type, an objection has been encountered in securing the composition facing to the board. By my invention, of which one embodiment is here illustrated and described, the facing member is securely attached and can not be 25 dislodged. The invention aims to secure the facing in position without other fastening means than that afforded by the configuration 30 of the rubbing member and the frame of the board.

These and other objects will be apparent 35 from the illustrated embodiment of my invention, it being understood that changes and alterations may be made within the scope of the invention and the attached claims.

In the drawings:

Figure 1 is a front elevation of one form 40 of wash board embodying my invention;

Figure 2 is a rear elevation;

Figure 3 is a longitudinal section on the line 3—3 of Figure 1; and

Figure 4 is a transverse section on the line 4—4 of Figure 3.

The wash board comprises the usual side 45 members 1 and the transverse top member 2, the soap board 3, and the upper and lower transverse partitions 4 and 5. The inner faces of the side members or bars 1 are provided with grooves 6 extending between the lower transverse member 5 and the top bar 2 in which grooves the several transverse pieces are tenoned and secured in any suitable manner.

The area between the cross bars 4 and 5 55 constitutes the rubbing surface and is occu-

pied by the rubbing element or mat 7. This mat is formed of rubber or a rubber-like composition with a roughened upper surface 8 of any suitable form. As here shown, the surface is formed with a plurality of comparatively fine sharp ridges or serrations making the required roughened surface. Beneath the mat are arranged a plurality, here shown as three, of backing members or slats 9 arranged transversely of the rubbing surface and spaced apart as shown. The horizontal edges of the backing members are preferably inclined or beveled outwardly and between the edges are received dovetail ribs 10 integral with the mat. The upper 60 and lower edges of the mat fit in grooves 11 in the transverse bars 4 and 5 and are formed with half dovetail ribs 12 which engage the edges of the adjacent backing members. The vertical edges of the mat and the 65 backing members are received in the grooves 6 in the side frames 1.

While the backing members and ribs are shown as dovetailed so as to secure a firm seating of the rubber mat, their formation 70 may be varied. I believe that I am the first to construct a wash board of this type in which the rubber or composition mat or rubbing surface is secured so as to be retained 75 in position against the severe strains to 80 which it is subjected, and as such I am entitled to all equivalents in the construction and scope of the appended claims. This result is preferably accomplished without the use of metallic or extraneous fastening devices and without the use of any fabric or 85 similar material incorporated with the rubbing surface.

What I claim is:

1. A wash board comprising, side frames 90 and transverse members, a facing in the form of a continuous sheet forming the rubbing surface, a plurality of separate spaced transverse backing members beneath the facing member and parallel ribs extending 95 transversely of the back of the facing member and integral therewith and received between the several backing members.

2. A wash board comprising, side frames 100 and cross bars, a mat forming the rubbing surface of the board, a plurality of spaced backing members extending across the side frames, ribs integral with the mat at the upper and lower edges and received between the cross bars and the transverse members, 105 110

and additional transverse ribs integral with the mat and received between the edges of the spaced backing members.

3. A wash board comprising, side frames and cross bars, a rubber mat forming the rubbing surface of the board, a plurality of spaced transverse backing members extending across the board beneath the mat, and parallel transverse ribs integral with the mat and dovetailed, said ribs fitting between the backing members and serving to secure the mat in position.

4. A wash board comprising, side frames and cross bars, the side frames being grooved, a rubber mat forming the rubbing surface of the board, a plurality of spaced transverse backing members extending between the side frames, and integral ribs on the under side of the mat received between

the backing members, the vertical edges of 20 the mat and the backing members being received in the grooves on the side frames.

5. A wash board comprising, grooved side frames and cross bars, a rubber mat forming the rubbing surface of the board, a plurality of spaced transverse backing members extending between the side frames, the edges of the mat being received in the grooves on the cross bars and the side frames, and the ends of the transverse members being received in the grooves on the side bars, and integral dovetail ribs arranged 25 horizontally on the rear of the mat and received between the cross bars and the adjacent transverse members, and between the 30 several transverse members. 35

RALPH M. REEL.
